Lighters Limited, a British company

Filed Dec. 18, 1964, Ser. No. 83,086

Claims priority, application Great Britain, July 20, 1964

Term of patent 14 years

(Cl. D85—8)

Fig. 1.

Fig. 2.

Fig. 3.

Fig. 4.

The broken line showing of a smoker's pipe bowl and mouthpiece in FIG. 2 is for illustrative purposes only.

The characteristic feature of my design resides in the combination with a ribbed pipe stem portion having the configuration shown of the relatively thin smooth spigot for supporting a pipe bowl.

I claim:

The ornamental design for a stem for a smoker's pipe, substantially as shown and described.
